CLAIM

The ornamental design for a hitch assembly as shown and described.

DESCRIPTION

FIG. 1 is a front side perspective view of the hitch assembly of the present invention;

FIG. 2 is a rear side perspective view thereof;

FIG. 3 is a right side view thereof;

FIG. 4 is a left side view thereof;

FIG. 5 is a top view thereof;

FIG. 6 is a bottom view thereof;

FIG. 7 is a front view thereof;

FIG. 8 is a rear view thereof; and,

FIG. 9 is a front side perspective view of the hitch assembly in its environment of use.

The broken lines illustrate the environment in which the hitch assembly is embodied and form no part of the claimed design.
